CLAIM

The ornamental design for a multi-depth spiral milli fluidic device for whole mount zebrafish antibody staining as shown and described.

DESCRIPTION

FIG. 1 is a perspective view of a multi-depth spiral milli fluidic device for whole mount zebrafish antibody staining showing our new design.

FIG. 2 is a bottom view thereof.

FIG. 3 is a top view thereof.

FIG. 4 is a left side elevational view thereof.

FIG. 5 is a right side elevational view thereof.

FIG. 6 is a rear elevational view thereof; and,

FIG. 7 is a front elevational view thereof.
